DESIGN FOR A FLYING MODEL HELICOPTER TOY

Wiley K. Crowder, Detroit, Mich.

Application June 26, 1946, Serial No. 131,024

Term of patent 14 years

(Cl. D34—15)

To all whom it may concern:

Be it known that Wiley K. Crowder, a citizen of the United States of America and a resident of Detroit, in the county of Wayne and State of Michigan, has invented a certain new, original, and ornamental Design for Flying Model Helicopter Toy, of which the following is a specification, reference being had to the accompanying drawing, forming a part thereof, and wherein:

Fig. 1 is a perspective view of a flying model helicopter toy embodying my design; and

Fig. 2 is a rear elevational view thereof.

The present application is a continuation in part of applicant's prior application Serial No. D-122,206, filed February 20, 1945, which is now abandoned.

I claim:

The ornamental design for a flying model helicopter toy, substantially as shown.

WILEY K. CROWDER.
